US00D611854S

(12) **United States Design Patent**
Wang et al.

(10) **Patent No.:** US D611,854 S
(45) **Date of Patent:** ** Mar. 16, 2010

(54) **ANALYTE SENSOR**

(75) Inventors: **Yi Wang**, Sam Ramon, CA (US); **Joseph A. Vivolo**, San Francisco, CA (US); **Shridhara Alva Karinka**, Pleasanton, CA (US)

(73) Assignee: **Abbott Diabetes Care Inc.**, Alameda, CA (US)

(**) Term: **14 Years**

(21) Appl. No.: **29/344,579**

(22) Filed: **Sep. 30, 2009**

Related U.S. Application Data

(63) Continuation of application No. 11/281,883, filed on Nov. 17, 2005, which is a continuation-in-part of application No. 10/866,477, filed on Jun. 12, 2004, which is a continuation of application No. 10/033,575, filed on Dec. 28, 2001, now Pat. No. 6,749,740, which is a continuation of application No. 09/434,026, filed on Nov. 4, 1999, now Pat. No. 6,616,819.

(57) **CLAIM**

The ornamental design for analyte sensor, as shown and described.

DESCRIPTION

FIG. 1 is a schematic front view of an exemplary analyte sensor, with no claim made to the portion shown in phantom; and,

FIG. 2 is a schematic rear view of the analyte sensor of FIG. 1, with no claim made to the portion shown in phantom.

1 Claim, 2 Drawing Sheets

FIG. 1

FIG. 2
